(57) **CLAIM**

The ornamental design for the in-desk mounted cable box with integrated touch panel, as shown and described.

DESCRIPTION

FIG. 1 is a perspective front left view of the in-desk mounted cable box with integrated touch panel of the present invention.

FIG. 2 is a top view of the in-desk mounted cable box with integrated touch panel of FIG. 1;

FIG. 3 is a perspective front right view of the in-desk mounted cable box with integrated touch panel of FIG. 1;

FIG. 4 is a left side view of the in-desk mounted cable box with integrated touch panel of FIG. 1;

FIG. 5 is a front view of the in-desk mounted cable box with integrated touch panel of FIG. 1;

FIG. 6 is a right side view of the in-desk mounted cable box with integrated touch panel of FIG. 1;

FIG. 7 is a perspective rear left view of the in-desk mounted cable box with integrated touch panel of FIG. 1;

FIG. 8 is a bottom view of the in-desk mounted cable box with integrated touch panel of FIG. 1; and,

FIG. 9 is a perspective rear right view of the in-desk mounted cable box with integrated touch panel of FIG. 1.
